ISAAC F BAKER's

DESIGN FOR FURNITURE ORNIMENTS.

"LAST OF THE MOHICANS"

Patented Dec 5th 1848

19206

From Johnson & Rob

Des. 206

Isaac F. Baker Philadelphia Pennsylvania

Letters Patent No. 206 Dated Dec. 5, 1843

Assigned to Lorraine Company

The schedule referred to in the schedule, patent and in
making part of the same.

To all whom it may concern: Be it known that I Isaac F.
Baker of the City & County of Philadelphia and State of Penn-
sylvania have invented a new & useful design for furni-
ture ornaments called the Last of the Mohicans & that
the following is a full, clear & exact description thereof
of reference being had particularly had to the accom-
panying drawing which represents a group of three
human figures all in the habiliments of hunters.
The heads of two being represented as ornamented with
feathers, and that of the third as covered with a cap.
The last mentioned figure I call Leather Stocking, & I
have marked it A, in the drawing. The figure marked
B. I denominate Ching-a-cook & the figure marked
C I designate as Uncas. These three figures are
capable of being used separately by detaching each
from the general group & casting it by itself as a
separate ornament; but with C I shall chiefly use as
an ornament for furniture such as the base of a branch
candle stick, gas fixtures &c. &c. & in this great variety

ding with three figures & above mentioned with the foliage
herein the same bended and all the other parts repre-
sented in the drawing herein arranged.

What I claim as my invention I desire to secure by
letter patent is the entire design represented in the
drawings and herein described.
